UNITED STATES PATENT OFFICE.

LAURA GALLINEK, OF NEW YORK, N. Y.

KNIFE.

1,372,807.

Specification of Letters Patent. Patented Mar. 29, 1921.

Application filed June 5, 1920. Serial No. 386,683.

To all whom it may concern:

Be it known that I, LAURA GALLINEK, a citizen of the United States, residing at New York city, in the county of New York and State of New York, have invented certain new and useful Improvements in Knives, of which the following is a specification.

My invention relates to improvements in folding pocket knives.

One object of the invention is to provide a device of this character which is simple in construction, effective in operation and which can be produced at a minimum cost.

Another object is to provide a handle stamped from a single blank, incasing one or more knife blades, which may be held in open or closed position without employing the usual knife back spring.

20 In the accompanying drawings,

Figure 1 is a perspective view of my improved pocket knife;

Fig. 2 is a bottom plan view showing one blade extended and the other closed;

25 Fig. 3 is a vertical sectional view showing the relative positions of the blades and their locking hooks.

Referring to the drawings, 10 indicates the handle or shell portion comprising two 30 parallel sides 11 and connecting web portion 12 forming the back of the handle. A transverse rivet 13 adjacent each end of the shell 10 and located centrally of the width of sides 11 form the pivots for the opposed

35 knife blades 14.

The knife blades 14 are provided with elongated openings or slots 15 located in the tang or butt end 14^a and are adapted to permit longitudinal and arcuate movement 40 of the blades about the pin 13. The back of the blade, or that part which has a blunt edge, is provided with two hook shaped projections 15^a and 15^b, each of which is adapted to overlap or engage the back portion or web 12 of the shell 10 when the blade is extended or open. The back or web 45 12 is provided with a slot 16 adjacent each end, to accommodate the lateral movement of the hooks 15^a, 15^b and 17 and also to provide a hooking edge for each. The hook 50 15^a overlaps or hooks over the end of the web 12 beyond the slot 16. The cutting edge of the blades 14 is provided with a single hook shaped projection 17 at the butt end 14^a,

55 which is adapted to overlap or engage the inner edge of the slot 16 nearest to each of

the ends of the shell 10, said hook 17 being used only when the blades are closed within the shell or handle member. An arc shaped recess 18 is located at the front edge of each 60 of the sides 11 to permit the fingers to grip the blades 14 as the latter are being opened.

In the operation of the knife pertaining to the opening or closing of the blades 14, particular reference is called to Fig. 3. To 65 open a blade the latter must be moved lengthwise until the hook 17 is free of the web 12 at which time the pivot pin 13 will have engaged the rear end of the slot 15. The blade 14 is then swung outwardly 70 about the pin 13 until the axis of the blade is aligned with the axis of the handle, whereupon the blade 14 is pushed inwardly, the slot 15 guiding said blade until the pin 13 contacts with the forward end of the slot. 75 During the receding of the butt 14^a of the blade 14 within the shell 10, the hook projection 15^a and 15^b will come into engagement with the edges of the slot 16 and end of the web 12. It will be noted that the construction adapted for locking the blade in open position forms a triangular support 80 against backward or forward arcuate movement of the blade 14. Each of the hooks 15^a and 15^b, while hooked to the back or shell 12 is prevented from acting as a fulcrum for the other by the pin 13, which receives the bulk of the strain and equalizes the pressure brought to bear against each hook. 85

To close the blade 14 the latter will be pulled out until the hooks 15^a and 15^b are disengaged from the back or web 12. The blade is then swung about the pin 13 until the blunt portion of the butt 14^a contacts 90 with the inner edge of the back or web 12. The hook 17 will enter and protrude above the slot 16, whereupon a slight outward movement of the blade 14 toward the end of the shell or handle will bring the said hook into engagement with the end portion of the web 12 locking the latter within the handle. The blades are pivoted at each end of the handle 10 and are folded in an arcuate movement toward each other, and when 100 closed they will be side by side within the handle. 105

I claim:

1. In a folding pocket pen knife, the combination of a U-shaped shell member having slots adjacent the ends thereof, and transverse pivot pins between the walls of 110

said shell adjacent the ends thereof, knife blades each having a tang provided with a slot therein adapted to embrace one of said pivot pins, and hooking means provided for 5 securing said blades either in closed or open position by engaging said hooking means with said slots in the shell member.

2. A pen knife comprising a handle member having a slot in its rear wall, and a 10 blade pivoted in said handle member, said blade having hooks at the opposite edges of its tang adapted to engage the end walls of said slot whereby said blade may be locked in open or closed position.

3. A pen knife comprising a handle member having an elongated slot in its rear wall, a blade pivoted in said handle member, a pair of hooks carried by the rear edge of the tang of said blade and adapted to engage the end walls of said slot when the 20 blade is open, and an additional hook carried by the front edge of the tang of said blade and adapted to engage one of the end walls of the slot when the blade is closed.

In testimony whereof I have affixed my 25 signature.

LAURA GALLINEK.
